C. H. McCORMICK.

Side-Hill Plow.

Patented June 13. 1831.

Cyrus H. McCormick
Bellow Patent

The Schedule referred to in these Bellow Patents and making part of the same containing a description in the words of the said Cyrus H. McCormick himself of his improvement in the Hill side Plough

Be it known that Cyrus H. McCormick of Rockbridge County State of Virginia have made an improvement in the Hill side Plough which is described as follows. This plough consists of the following parts 1st The share is the mould board with its brace or beam, handles, & standards or hinder supports. 4th The lower brace bar. 5th The lock ingrod & lever. 6th The fulcrum or spring of the brace bar. 8th The pivot and screw. 11th The share The share is made double of iron & steel with a point at each end and a double wing on the same side of each end of the share, at the instance of the point of the mould board is a pin against which the mould board looks and is kept in its place. At a proper distance from the point of the share are two holes one at each end to receive those as to be hereafter described.

2nd The mould board with its brace The mould board is made double with a brace extending between the two of supporting beam. This which brace are two holes one over each end to receive a pin or locking pin to be hereafter described. Now the front end is quite thin the mould board is a hole this which a pin or rod is to pass to be also hereafter described. 3rd The beam handles & standards or hinder supports The beam handles are made in the usual form of a suitable size and strength, a hole is made thru the beam to receive the pin or rod. The standard or hinder support is made of any convenient size it is placed at the end of the beam and has a hole mortised in it to receive the tenon of the beam. also a mortise thru which a brace passes to support the handles. At the lower end of it is fitted the lower brace bar to be next described.

4th The lower brace bar This is made of iron and extends from the beam and hinder support to about the middle of the share and has an opening

openings to let the pivot and pins pass. It is made fast to the standard or hinder support. There is also another hole near the middle of the bar this which the locking rod passes into the share. 5th The locking rod & lever. The long locking rod passes down thru the beam this, the lower brace bar into the share having a shoulder on the upper side of the bar to prevent its going too far, and another shoulder or projection even with the upper side of the beam; to be operated on by a spring to be hereafter described. This rod extends thru an opening made in the spring, and has a hook or screw at the upper end to attach it to the lever. Another locking rod is riveted to the spring & passes thru the beam and the holes made near each end of the brace bar of the mould board. The lever is made of any convenient length & moves on a fulcrum placed beside the spring & is attached to the first mentioned locking rod. There is a pin or projection on the standard or hinder support to hold it to its place whilst turning the plough. 6th The fulcrum & spring. A piece of iron forming the fulcrum ^{is} fastened to the beam and rising two or three inches above the spring, on the top of which is placed the lever. The spring is made of iron or steel and is fastened to the beam. At proper distances, openings are made to let the pivot rod and long locking rod pass. The other locking rod as mentioned before is riveted to this spring. 7th The brace rod passes thru the standard or hinder support to the beam near where it is connected with the mould board. There is a hole thru one end of this end, this which the pivot rod passes, the other end passes thru the standard or hinder support & lower brace bar & is fastened with a screw. 8th The pivot rod & nut. The pivot rod is made iron or steel this the share, the lower brace bar, mould board, beam & spring is fastened with a nut on the top. Operation. When it is required to turn the furrows all one way, the first furrow being run, the lever is pressed down and fastened by the pin on the side of the standard or hinder support, by which the long locking rod is drawn out of the share, the upper shoulder of which now carries the spring and consequently draws the other locking pin out of the mould board.

land brace, all being now loose, the plough is turned, the share remaining stationary, and the mould board turned till stopped by the pin in the share, & which produces the required change in the plougher so as to throw the most furrow the same with the first. Then disengaging the brace, the spring operates on both the locking rods to fasten both the mould board & share together and the ploughing is commenced. This plough can also be used as a common plough. What I claim as my invention is the combination and arrangement of the different parts of the above described plough so as to effect the turning and securing the mould board, and other parts of the plough to the share but particularly in making the mould board to turn whilst the share remains stationary and afterwards locking it to the share, together with an improvement in the construction of the share.
